UNITED STATES PATENT OFFICE.

DWIGHT W. WADSWORTH, OF BANGOR, MICHIGAN.

SPARK-PLUG.

988,840.

Specification of Letters Patent.

Patented Apr. 4, 1911.

Application filed September 28, 1909. Serial No. 518,942.

To all whom it may concern:

Be it known that I, DWIGHT W. WADSWORTH, a citizen of the United States, residing at Bangor, in the county of Van Buren 5 and State of Michigan, have invented new and useful Improvements in Spark-Plugs, of which the following is a specification.

This invention relates to improvements in spark plugs for internal combustion engines, 10 the object of the invention being to effect improvements whereby the spark plug is provided with a plurality of spark gaps so that a number of electric sparks will be produced at each closing of the electric circuit and ignition of the explosive gases in the engine 15 made certain as hereinafter described and claimed.

In the accompanying drawings:—Figure 1 is an elevation of a spark plug showing one 20 form of this invention. Fig. 2 is an end view showing the exposed end of the plug. Fig. 3 is a detail elevation of the insulating core showing the inner conductor and also showing one of the spark gaps. Fig. 4 is an 25 elevation showing a modified construction of the insulating core. Fig. 5 is an end elevation of the same.

The insulating core 1 in which the inner conductor 2 is disposed is here shown as fitted in the usual metal shell 3 and is detachably secured therein by the usual screw sleeve 4. In accordance with my invention 30 that portion of the inner conductor which is located at the exposed or inner end of the insulating core is made of a plurality of sections, four of such sections being shown at 5 in Fig. 2 and three being shown at 6 in Fig. 5. In the form of the invention shown in Figs. 1, 2, and 3, said sections are embedded 35 in the insulator core 1 and the latter has a head 7 at its exposed end which head is provided with recesses 8 which expose the ends of said embedded sections of the inner

conductor, said sections being separated from each other so as to form a plurality of 45 spark gaps or air gaps 9 between them. One of the sections or electrodes 5 is spaced from and presented to an outer electrode 10 which is secured on the shell 3 so that another spark or air gap is formed between said 50 section and said outer electrode 10.

It will be understood that each time an electric circuit is completed through the conductor, the separated sections thereof which constitute a series of separated electrodes will cause a plurality of sparks to be produced and hence ignition of explosive 55 gases or mixture in the engine cylinder will be insured.

In the form of the invention shown in 60 Figs. 4 and 5, the separated sections or electrodes 6 of the conductor project from the exposed end of the insulating core. Other modifications may be made within the scope 65 of the appended claim.

What is claimed is:—

A spark plug comprising a metal shell, a core of insulating material secured within the metal shell and having a head at its inner end provided in its sides with a series 70 of recesses forming spaced portions, a conductor secured within the insulated core, an electrode connected with said metal shell, and a series of conductor sections supported in the spaced portions of the head at the 75 inner end of the insulated core and having their ends exposed and in close relationship, whereby a plurality of spark gaps are formed.

In testimony whereof I affix my signature 80 in presence of two witnesses.

DWIGHT W. WADSWORTH.
